UNITED STATES PATENT OFFICE.

WALTER E. SCHUSSLER, OF PHILADELPHIA, PENNSYLVANIA, ASSIGNOR TO THE SCHUSSLER TOBACCO MACHINE COMPANY, OF PHILADELPHIA, PENNSYLVANIA, A CORPORATION OF PENNSYLVANIA.

CIGAR-BUNCHING MACHINE.

Application filed January 8, 1924. Serial No. 684,944.

The object of my present invention is to provide a cigar bunching machine of novel construction and to provide novel means for making the bunch, with the correct amount or weight of tobacco contained therein, novel means of distributing the tobacco to produce the form desired, and novel means of applying the binder to prevent it from being curled up by the rolling apron during the rolling operation.

With the above and other objects in view which will hereinafter more fully appear, my invention comprehends a novel construction and arrangement of a cigar bunching machine, and a novel mechanism for making the bunches.

It further comprehends a novel construction of weighing mechanism which controls the stopping of the feed of the tobacco passing to said weighing mechanism.

It further comprehends novel means to deliver the tobacco in a form of any desired shape to the bunching mechanism, and novel means for placing a binder of small size about the filler.

Other novel features of construction and advantages will hereinafter more fully appear in the detailed description and the appended claims.

For the purpose of illustrating my invention, I have shown in the accompanying drawings a typical embodiment thereof which is at present preferred by me, since this embodiment will be found in practice to give satisfactory and reliable results. It is, however, to be understood that the various instrumentalities of which my invention consists can be variously arranged and organized and that my invention is not limited to the precise arrangements and organization of these instrumentalities as herein shown and described.

Figure 1 represents a front elevation of a cigar bunching machine, embodying my invention.

Figure 2 represents a section on line 2—2 of Figure 1.

Figure 3 represents a plan view showing the construction above the line 3—3 of Figure 1.

Figure 4 represents a partial side elevation with part of frame broken away.

Figure 5 represents a plan view of a tobacco receptacle.

Figure 6 represents a side view of a released mechanism and feed drive.

Figure 7 represents a view similar to Figure 6, but in another position.

Figure 8 represents an end elevation of the feed drive mechanism.

Figure 9 represents a plan view of a feed drive pawl.

Figure 10 represents a half plan view of binder controlling mechanism.

Figure 11 represents a section, on line 11—11 of Figure 2, of binder controlling mechanism.

Figure 12 represents a side elevation of Figure 11.

Figure 13 represents a similar view as Figure 12 but in operative position.

Figure 14 represents a plan view of a scale pan.

Figure 15 represents a side elevation, partly in section.

Figures 16 and 17 represent, respectively, in front elevation other forms of shaping devices, embodying my invention.

Figure 18 is a side view of the upper portion of Figure 1, taken from the left hand side thereof and on an enlarged scale.

Similar numerals of reference indicate corresponding parts.

Referring to the drawings:

In my prior application, Serial No. 541, 914, March 8, 1922, I have described and broadly claimed a novel construction of an automatic cigar bunching machine. My present invention has the same general cycle of operation, but many of the mechanisms employed have been improved and simplified in order to increase the efficiency of the machine.

1 designates the main frame of the machine, and 2 is the portion thereof which carries the feeding and weighing mechanism. 3 designates the main driving belt which passes around the main driving pulley 4, which is fast to a main driving shaft 5, mounted in bearings 6 and 7, which are carried by the frame 1. The shaft 5 is provided with a worm 8, see more particularly Figure 2, and meshes with a worm wheel 9 which is loosely mounted on a main cam shaft 10, which latter is journalled in bearings 11 and 12 carried by the main frame 1. The worm wheel 9 has integral with it a ratchet 13.

- 14 designates a driving pawl, which is loosely mounted on a stud 15, fixed to a lever 16, which latter is fixed to the shaft 10. The rear end of the pawl 14 has connected to it one end of a spring 17, the opposite end of which is connected to the lever 16. In order to prevent relative longitudinal movement of the shaft 10 in its bearings, a pin 18 extends therefrom, see the lower right hand portion of Figure 1. The pawl 14 is provided with a release lever 19 which is fixed on a rock shaft 20. A lever 21 is also fixed on the rock shaft 20, and is provided with a stud 22 on which is loosely mounted one end of a link 23, the opposite end of which is loosely mounted on a stud 24 carried by a foot treadle lever 26 which is fixed to a rock shaft 25, suitably journaled in the machine frame.
- 20 The movement of the release lever 19 in one direction is limited by means of a stop pin 27 carried by the machine frame. A stud 28 carried by the machine frame has fixed to it one end of a spring 29, and the opposite end of said spring is connected with the release lever 19, so that the tendency of such spring is to maintain the release lever 19 against the stop pin 27.

In order to prevent longitudinal movement of the shaft 20 in the main frame, I provide a pin 30, and, in order to prevent lateral movement of the shaft 25 in the main frame, I provide pins 31 and 32, see Figure 1. The shaft 10, see Figure 2, has secured to it a cam 33. Spaced from the cam 33 and fixed to the shaft 10 is a second cam 34, see Figure 1. The main frame 1 has journaled in it a rock shaft 35, and longitudinal movement of this shaft with respect to the main frame is prevented by the pins 36, see Figure 1. The shaft 35 has loosely mounted on it a cam lever 37. 38 is a cam roller, see Figure 4, which travels in a cam groove 39 of the cam 34. This cam roller 38 is loosely mounted on a stud 40 carried by the lever 37. The cam lever 37 has fixed at its free end a stud 41 to which is connected one end of a link 42, the opposite end of said link being connected to a stud 43 carried by an arm of a bell crank lever 44 which is fixed to a rock shaft 45, suitably journaled in the bearings 46, carried by the main frame 1.

The bell crank lever 44 has an arm 47 which carries a trip pawl 48 mounted on a stud bearing 49 fixed to the lever arm 47, and a stop pin 50 carried by the arm 47 limits the movement in one direction of said trip pawl 48. 51 designates a trip lever, provided with a cam face 52 and fulcrumed on a stud 53 fixed to a bearing 54 which forms a part of a plate 55.

The rolling table 56 which is a part of the frame 1, receives the plate 55.

65 The lever 51 has a stud 57 on which is

loosely mounted one end of a link 58, the opposite end of which is loosely mounted on a stud 59 secured to one end of an arm 60. The other end of the arm 60 is secured to a shaft 61 journaled in the machine frame.

A scale operating arm 62 is fixed at one end to the shaft 61 and is adapted to co-operate with an arm 63 secured to the hopper 64 of the scale pan. The scale pan, see Figure 14, has a back wall 65 from which extend the arms 66. The scale pan is fulcrumed at 67, and the hopper is fulcrumed at 68 to the back wall of the scale pan. 69 and 70 designate scale arms fixed to a shaft 71, mounted in bearings 72 and 73 carried by the frame portion 2 of the machine frame.

The shaft 71 has secured to it a balance arm 74 which carries an adjustable weight 75 and a fixed balance weight 76, see Figure 3. The shaft 71 is provided with a stop lever 77, having at its free end a tooth 78, said lever having its movement in one direction limited by a stop pin 79, secured to a fixed portion of the machine frame.

80 designates a ratchet wheel, loosely mounted on a shaft 81 journaled in the machine frame. 82 designates a lever loosely mounted on the shaft 81, see Figures 6 and 7, and provided with a pin 83 which extends beneath the lever 77 to actuate it. The lever 82 is retained in position by a stop pin 84, see Figure 1. The lever 82 has a stud 85 on which is fulcrumed one end of a link 86, the other end of said link 86 being fulcrumed on a stud 87, secured to one end of an operating lever 88 loosely mounted on the shaft 45, see Figure 1. The lower arm 89 of the lever 88 carries a stud 90, on which is loosely mounted a roller 91, which is actuated by the cam 33, see also Figure 2. The lever arm 89 has a stop projection 92 adapted to contact with the rolling table 56. 93 designates a spring pin fixed to the table 56, and a spring 94 is connected with the spring pin 110 93 and with the lever arm 89 to retain its lever 88 in its normal position.

Referring now more particularly to Figures 6, 7 and 8, the ratchet wheel 80 has fixed to it a pawl operating pin 95, and also a spring stud 96, to which is connected one end of a spring 97, the opposite end of which is connected to a spring stud 98 carried by an arm 99, which is an operating arm secured to the shaft 81. The arm 99, see Figure 8, has a spring stud 100 to which is connected one end of a spring 101, the opposite end of said spring being connected to a spring stud 102 secured to a driven pawl 103 fixed to a rock shaft 104 loosely mounted on the arm 99.

The pawl 103 has a tooth 105 co-operating with the teeth of a driving ratchet wheel 107 fixed to a worm wheel 108, both of which are loosely mounted on the shaft 81. The

pawl 103 has a slotted arm 106 to receive the pin 95. The shaft 81 is journaled in bearings 109 and 110, see Figures 2 and 3, and a worm shaft 113 is journaled in bearings 111 and 112, see Figure 3, and is provided with a worm 114.

The shaft 113 has a drive pulley 115, and the shaft 5 has a drive pulley 117. A driven belt 116 drives the pulley 115 and also the pulley 117. 118 is a feed belt for the shaft 81; see Figure 4. A feed belt 119 passes around the shaft 81 and around a pulley 122 on a shaft 121 journaled in the frame.

A drive belt 123 passes around the pulley 122 and around a pulley 124 on a tobacco spreader shaft 125, journaled in bearings 127 and 128, and this shaft 125 has fingers or prongs 126 which spread the tobacco.

Secured to the frame portion 2 are tobacco guides 129 and 130, see Figure 3. 133 designates a pusher, see Figure 5, which travels between laterally adjustable guides 131 and 132 which are fixed in their adjusted positions on the plate 55 by fastening devices 171. The pusher 133 slides on the plate 55, and has lugs 134, to which is fulcrumed, at 135, a link 136, connected with a rod 137, secured to a lever 138 loosely mounted on the shaft 45. The end of the lever 138 has a pin 139 which co-operates with a lug 140 on the cam 34, see Figure 4. 141 is a spring pin secured to the frame and connected by a spring 142 with the lever 138 to maintain such lever against a stop 143. A guide 131, see Figure 1, has an inclined chute or shaper 144. 145 designates an apron carriage mounted on slide rods 146 and 147, and the carriage has bearings 148 and 149 for a shaft 150, see Figures 11 and 12.

The apron roller 151 revolves freely on the shaft 150, and a shield 152 partly covers such roller and has bearings 153, free to rock on the shaft 150. A spring pin 154 is secured to one of the bearings 153, and is connected by a spring 155 with a spring stud 156, secured to the apron carriage 145. A stop pin 157 is secured to a bearing 153. The rolling apron 158 is secured, at its rear, to the main frame by a clamp 159, and, at its front, by a clamp 160. 161 is a flexible strip carried by a clamp 163 to smooth out the binder 162, shown in dot and dash lines in Figures 12 and 13. The clamp 163 has at opposite ends lugs 164, secured to rods 165, slideable in bearings 166 and 167, which are a part of the apron carriage 145. A compression spring 168 retains the strip 161 against the shield 152, when the parts are in the position seen in Figure 13, and a stop pin 169 holds the spring in position on the rods 165. The apron 158 has a pocket 170 to receive the tobacco, prior to the bunching operation.

By employing different forms of shapers,

the shape of the finished cigar can be varied as may be desired. Instead of employing a shaper such as the shaper 144 which causes the cigar to be thicker near one end, a shaper such as 172, in Figure 16, or 173, as seen in Figure 17, can be employed.

The operation of my novel cigar making machine will now be apparent to those skilled in this art and is as follows:

The first step in the cycle of the operation is the placing or feeding of tobacco to the feed belt 119 in rear of the spreader 126, and I will now describe the different mechanisms in the logical order in which they are brought into operation.

The main driving shaft 5 is driven by means of any desired type of power, and is effective to drive the belt 116, (see Figure 1), said belt also passing around the pulley 115 on the shaft 113 (see Figures 1 and 3). The worm 114 meshes with the worm wheel 108 on the shaft 81. The shaft 81 has mounted on it the ratchet wheels 80 and 107, (see Figures 6, 7, and 8). The ratchet 107 is integral with the worm wheel 108, and drives the pawl 103 which, in turn, drives the arm 99 which is fixed to the shaft 81. The pawl 103 receives the pin 95 carried by the ratchet 80, so that when the pawl 103 is driven, the ratchet wheel 80 will also be driven. When the ratchet wheel 80 revolves, the shaft 81 will revolve in unison with it. The drum 118 (see Figure 2) is fast to the shaft 81, and, as the feed belt 119 passes around this drum, the feed belt will be driven, thus feeding the tobacco. The roller 120 around which the feed belt 119 passes, is fast on the shaft 121 on which is fixed the pulley 122 around which the belt 123 passes, which, in turn, passes around the pulley 124 on the shaft 125 which carries the feeding elements 126. This causes the tobacco to be spread in a uniform layer on the feed belt, between the guides 129 and 130. The feed belt 119 delivers the tobacco to the scale pan 64. As soon as the predetermined amount of tobacco has been received in the scale pan, the scale pan drops, and the feed of tobacco is automatically arrested in a manner which will now be described. As soon as the scale pan drops, the lever 77 which is fixed to the shaft 71 on which the scale pan is fulcrumed moves from the position seen in Figure 6 into that seen in Figure 7, so that the tooth 78 of the lever 77 engages a tooth of the ratchet wheel 80, and stops its rotation. This brings the pin 95 to a stop, which causes the pawl 103 to be raised from its operative position seen in Figure 6 into its inoperative position seen in Figure 7. The spring 101 retains the pawl 103 in its inoperative position until the feeding operation again begins. Referring now more particularly to Figures 2 and 4, the main driving shaft 5 is intergeared with

110
115
120
125
130

the shaft 10 which carries a cam 34 which actuates the lever 37. This lever 37 is connected by the link 42 with a lever 44 on which is mounted a trip 48 which cooperates 5 with the cam 52 of the lever 51 to raise said lever 51 and thereby link 58 and lever 60, causing the arm 62 to press against the arm 63, and causing the movable side 64 of the scale pan to open. This permits the tobacco 10 to drop into the tobacco retainer. As soon as the trip 48 passes beyond the shoulder 52, the lever 51 and connecting links will be permitted to drop downwardly, so that the movable side of the scale pan will close, due 15 to the manner in which it is supported. The scale pan is returned to its operative weighing position in the following manner. The shaft 10. (see Figure 2) has fixed to it a cam 33 which at the proper time cooperates 20 with the roller 91 to lock the lever 89, to thereby actuate the links 86, which in turn actuate the lever 82 which is loosely mounted on the shaft 81, (see Figure 6). The lever 82 has a projection 83, which presses against 25 the lever 77 and moves it into the position seen in Figure 6. The lever 77, as before explained, is fixed to the fulcrum scale pan, and therefore returns the scale pan to its operative or weighing position. The stop 30 79 prevents too great a movement of the lever 77. As soon as the tooth 78 of the lever 77 moves out of engagement with a tooth of the ratchet wheel 80, the spring 97, which is stronger than the spring 101, (see 35 Figures 7 and 8). will cause the ratchet wheel 80 to partially rotate, carrying with it the pin 95, which will cause the pawl 103 to move from the position seen in Figure 7 into that seen in Figure 6, and the operation 40 of feeding the tobacco will again begin.

By varying the shape of the shaper employed, such as for example 144, the shape of the finished cigar can be varied as may be desired, for example, shapers 172 or 173 45 can be employed. The adjustable guides 131 and 132 are relatively adjusted in accordance with the length of the cigar which is to be made. The next operation is the delivery 50 of the tobacco from the tobacco retainer into the pocket of the rolling apron, and this operation is as follows: The projection 140 on the cam 34 now contacts with the projection 139 which forms a part of lever 138, (see Figure 4) causing the lever 138 to move, 55 thereby actuating the link 136 to advance the pusher 133 and cause the tobacco to drop into the pocket of the rolling apron 158 on to the binder 162, (see Figures 12 and 13.)

60 The apron slide 145 is then moved in the proper direction to effect the formation of the bunch, in the usual and well known manner. In devices of this character as heretofore made there is a tendency of the binder 65 to be curled up by the apron passing around

the roller in its upward movement and contacting with it. In order to prevent such curling action, I provide the shield 152. This prevents the binder from touching the apron at this point and being carried up with the movement of the apron. The binder is held against the shield 152 during the rolling operation by means of a flexible trip 161, (see Figures 12 and 13). When the slide 145 is in normal position, as shown in Figure 12, 70 the rod 165 contacts with the frame, compressing the spring 168, so that, when the slide 145 is moved rearwardly, there will be a clear unobstructed passage for the tobacco to pass into the pocket of the rolling apron. 75 The clamp 163 is fixed to the rod 165, so that, when the slide 145 is moved rearwardly, the spring 168 will retain the rod 165 and thereby the clamp 163 and the flexible strip 161 in their forward position, as seen in 80 Figure 13. The shield 152 is loosely mounted, and has a tension device, so that, during the opening movement of the apron, the shield 152 is free to move with it.

In starting the machine, the operator 90 presses his foot on the foot pedal 26, thereby moving the release lever 19 out of contact with the pawl 14 and permitting the latter to drop and engage with a ratchet tooth 13 of the gear 9. This causes the opening of 95 the scale pan, the discharge of the weighed tobacco into the tobacco retainer, and the ejection of the tobacco from the tobacco retainer into the pocket of the rolling apron. It will be understood that the main shaft 100 10 has one revolution imparted to it, and it then stops until it is again set into operation by the operator placing his foot on the foot pedal 26.

In accordance with my invention, the tobacco, which in this case is principally short filler or scrap, is placed on the feed belt behind the spreader, or fed to such position in any desired manner. The tobacco is then advanced by the feed belt passing under 110 the spreader so that after passing the spreader, it is in practically a uniform layer. This tobacco is delivered to the weighing scale pan, and, when said scale pan has the determined weight of tobacco in it to overcome the balance weights, the scale pan descends, and thus brings the ratchet pawl on the scale fulcrum shaft into contact with the ratchet wheel, thereby stopping the feed 115 of more tobacco into the scale pan. From this scale pan, the tobacco is automatically discharged and fed into the apron pocket, and the bunch is then formed in the usual manner.

120 The cigar bunches can be made of short filler or scrap, and the tobacco is accurately weighed, so as to produce bunches of uniform size and weight as desired, and of a soft spongy nature, so they will be free-smoking.

125 A bunch of correct shape is required, and 130

this is accomplished by allowing the greater amount of the filler in the scale pan to fall into a desired position on the retainer below the scale pan, so that the tobacco will be 5 distributed as desired.

A binder of a smaller size is preferred in making cigars for the sake of economy in manufacture. The binder applying mechanism permits the laying of the binder diagonally in the rolling apron, and the end farthest from the roller is prevented from curling up by the shield partially surrounding the apron roller.

Having thus described my invention, what 15 I claim as new and desire to secure by Letters Patent, is:

1. In a cigar bunching machine, the combination with the rolling apron and the apron roller, of a shield in proximity to said 20 apron roller and capable of limited move-

ment in the direction of the movement of the apron.

2. In a cigar bunching machine, the combination with the rolling apron and the apron roller, of a shield movably mounted in 25 proximity to said apron roller and a tension device for said shield.

3. In a cigar bunching machine, the combination with the rolling apron and the apron roller, of a shield mounted in proximity to said apron roller, and a flexible strip 30 to cause a binder to contact with said shield during the rolling operation.

4. In a cigar bunching machine, the combination with the rolling apron and the 35 apron roller, of means to prevent the portion of a binder which has not passed into the apron pocket contacting with the apron as it passes upwardly over the apron roller.

WALTER H. SCHUSSLER.
